J. M. & W. I. DODDRIDGE.
GRAVE LINING.
APPLICATION FILED OCT. 5, 1908.

924,896.

Patented June 15, 1909.

Fig. 1.

Fig. 5

The diagram shows a horizontal beam with a central deflection curve. A horizontal dashed line represents the undeformed state of the beam. The deflection curve is labeled with a double-headed arrow indicating its magnitude. Points E and d are marked on the deflection curve. A coordinate system is established at the left end of the beam, with the horizontal axis labeled x and the vertical axis labeled y .

UNITED STATES PATENT OFFICE.

JAMES M. DODDRIDGE AND WILBUR I. DODDRIDGE, OF MILTON, INDIANA.

GRAVE-LINING.

No. 924,896.

Specification of Letters Patent.

Patented June 15, 1909.

Application filed October 5, 1908. Serial No. 456,130.

To all whom it may concern:

Be it known that we, JAMES M. DODDRIDGE and WILBUR I. DODDRIDGE, both citizens of the United States, and residents of the town of Milton, in the county of Wayne and State of Indiana, have invented certain new and useful Improvements in Grave-Linings, of which the following is a full and comprehensive specification, being such as will enable others to make and use the same with exactitude.

This present invention has reference to a two-part, upper and lower, grave-lining which may be easily made and placed in position, and which will give a pleasing and artistic effect to the grave.

The particular object of this invention is to provide a sectional fabrication for lining graves, the lower section being adapted to cover the interior of the vault or box, and the upper section adapted to cover the walls of the grave above the vault or box, whereby one of the sections may be removed without disturbing the other section.

Another object is to provide a grave lining formed of upper and lower sections, which will be neat and attractive in appearance, easily placed in position, and which can be manufactured and sold at a comparatively low price.

Other specific objects and particular advantages will be brought out in the course of the ensuing specification.

The method of construction and adaptation of our invention is clearly illustrated in the accompanying drawings, in which—

Figure 1 is a vertical longitudinal central section of a vault or grave with our invention in position thereon in operative position. Fig. 2 is a top plan view, as looking directly downward into the grave, with our invention in operative position. And Fig. 3 is a cross sectional view of the grave and our invention as taken on the line $x-x$ of Fig. 2.

Similar indices denote like parts throughout the several views.

For a more comprehensive understanding of our invention we will now describe the construction and specify the parts and the intended operation as compactly as we may.

In practice a grave is excavated in the ground 1 in the usual manner. A vault 2 may be formed of brick or the like, covering the bottom of the grave and extending up some distance on the sides and ends thereof, as shown, forming an off-set or ledge around

on the inside of the grave. Within the vault formed by the brick there may rest the usual rough box 3. Our invention is intended to cover all of said parts, and the invention consists essentially of but two parts or sections, divided horizontally. The lower section comprises, preferably, a single length of fabric A, having a ruffle a formed on the upper edge thereof. The length of the section A is such as to extend entirely around on the inside of the box 3, or the vault 2, forming but one vertical joint; and the length of section A is such as to cover the surface of the ledge formed by the vault and then extend down inside the box, or the vault, to the bottom, as indicated in Figs. 2 and 3. Secured to the back of section A, and located near to and parallel with the ruffle a, is a tape B, whose ends extend out beyond the ends of the section, where they may be tied together as at b in Fig. 2. In practice the upper edge of section A is brought to position with the tape B resting on the ledge where it may be secured by a plurality of pins or nails C, the pins or nails being pressed through the tape into the joints between the bricks or the like.

The upper edge of section A is formed full by gatherings, which can be done in forming the ruffle, thereby causing the section to hang in plaits or the like as indicated. The upper section D is formed substantially like the lower section, also being preferably formed in one piece of material, having a ruffle d formed along its upper edge. Secured to the back of section D and located near and parallel to the ruffle d is a tape E whose ends extend out beyond the ends of the section, where they may be tied together as at e in Fig. 2. When being positioned the upper edge of section D is brought out over the surface of the ground, with the tape resting on the ground, to which it is secured by a plurality of pins or nails F, said pins or nails being pressed through the tape into the ground, the tape and the pins being covered by the ruffle which is turned out there-over, as indicated, after the tape has been secured as stated. The lower edge of section D is adapted to reach down to the surface of the vault, or ledge, its lower edge being hidden by the ruffle a of section A. Section D is divided horizontally into a plurality of divisions by means of the shirring d'-d', which will produce a fullness and an artistic effect.

After the grave has been lined as shown and described it is apparent that the casket (not shown) may be deposited in the box 3, or the vault 2, after which the pins C may be 5 removed and the upper edge of the lower section folded in on top of the casket, after which the cover for the box, or the vault, may be placed in position and secured without, necessarily, removing section D from 10 position, thereby accomplishing the prime object of this invention.

By the above it is apparent that we provide a frameless grave lining formed wholly of fabric, with means for removing the major 15 or upper section of the lining after a casket has been secured in the grave. It is also apparent that each of the sections may, if desired, be formed into a plurality of separable parts, to be joined at the corners of the 20 grave in same manner as the two ends of the one-part sections are joined.

Having now fully shown and described our invention, what we claim and desire to secure by Letters Patent of the United States, is.
25 1. In combination with a grave, a frame-

less decorative lining therefor formed of fabric and comprising, essentially two, independent sections, one of which is for the lower portion of the grave and another for the upper portion of the grave, and means for securing the sections in position, all substantially as set forth.

2. A grave lining formed wholly of fabric and comprising two separate sections, each section being formed to extend entirely around on the inside of the grave, means for detachably securing the adjoining ends of each section together, means for detachably securing each of the sections in position independent of each other, and means for covering the securing means, substantially as described.

In testimony whereof we have hereunto subscribed our names to this specification in the presence of two subscribing witnesses.

JAMES M. DODDRIDGE.
WILBUR I. DODDRIDGE.
